D. C. O'SHEA

GARMENT

Filed July 16, 1921

Inventor:

Dennis C. O'Shea,
By Dyerforth, Lee, Christian & Miller,
Attorneys.

UNITED STATES PATENT OFFICE.

DENNIS C. O'SHEA, OF CHICAGO, ILLINOIS.

GARMENT.

Application filed July 16, 1921. Serial No. 485,270.

To all whom it may concern:

Be it known that I, DENNIS C. O'SHEA, a citizen of the United States, residing at Chicago, in the county of Cook and State 5 of Illinois, have invented a new and useful Improvement in Garments, of which the following is a specification.

This invention relates to improvements in garments, and more particularly to garments 10 adapted to be worn by players of foot ball, and similar sports. One form of garment embodying the features of my invention, is shown in the accompanying drawings, in which—

15 Fig. 1 is a view showing the garment in rear elevation, Fig. 2 is a view taken as indicated by the line 2 of Fig. 1, and Fig. 3 is a view of one of the pads used on the inside of the arm of the garment 20 showing the same folded out flat.

As shown in the drawings, 10 indicates in general a garment, here shown as made of knit material, or jersey cloth in the form of a shirt such as is ordinarily worn by 25 athletes, and commonly referred to as a jersey.

The back part of the jersey is provided with a downwardly extending tail or flap 11 having button holes 12 at its end. The 30 tail 11 is adapted to be folded around between the legs of the wearer from the back to the front. The tail or flap 11 when so folded prevents the jersey from being drawn upward on the body of the player and also 35 gives a supporting effect to the wearer.

The garment is provided with pads on the inside adapted to cover the shoulders, elbows and hips of the wearer. These pads vary somewhat in shape and size but they 40 are all made on the same principle, so I will describe in detail the construction of but one. I have indicated the shoulder pads, in general, by 40, and the hip pads, in general, by 42. One of the elbow pads is 45 shown more in detail in Figs 2 and 3, Fig. 2 being a sectional view through the sleeve of the garment where the pad is located, and Fig. 3 being a view of the pad from the inside of the garment, with the cloth 50 laid out flat. Each of the pads comprises a suitably shaped pad or piece of soft cushioning material. As here shown, this cushioning material is made out of skin or cloth covered with heavy fleece. I have 55 indicated the pad which has the fleece upon it by the numeral 50 and the fleece itself

by 51. In Fig. 3, for the purpose of illustration, the fleece 51 is shown as removed from a portion of the pad 50. The pad 50 which has the cushioning material upon it 60 is suitably fastened, as by sewing around the edge to a similarly shaped but somewhat larger patch 55 made of jersey cloth or other similar elastic or stretchy material. The patch 55 is enough larger than the 65 pad 50 to provide a margin about one inch wide around the entire edge of the patch. The patch 55 is attached to the garment by sewing on its outer edge as indicated by 70 56. It will be noted that the cushioning 70 pad 50 is nowhere sewed or otherwise attached directly to the garment itself. The cushion pad 50 is sewed or fastened to the larger patch 55, and this larger patch 55 is sewed on its outer edge to the garment. 75 By this construction, and because of the fact that the patch 55 is made out of elastic material, more or less displacement of the pad 50 is permitted with respect to the garment itself. In other words, the pad 50 80 by stretching of the marginal edges of the patch 55 is permitted to slide in all directions with respect to the garment 10. This construction permits a certain amount of displacement or sliding of the pad 50 when 85 a wearer of the garment falls on the ground with a sliding movement. Such sliding or movement of the pad makes the tearing of the garment or the ripping loose of the pad from the garment less likely. 90

Although the present invention has been described in connection with the specific details of a device embodying it, it is not intended that these details shall be regarded as limitations upon the scope of the invention except in so far as included in the accompanying claims. 95

What I claim as new and desire to secure by Letters Patent is:

1. A garment having secured to its surface 100 a patch of elastic stretchy material, and a pad of cushioning material secured to said patch, the means securing the pad to the patch spaced from the means securing the patch to the garment, whereby relative 105 movement between the pad and the garment may be permitted by stretching of a portion of the patch.

2. A garment having secured to its inner surface a patch of elastic stretchy material, and a pad of cushioning material secured to said patch, the means securing the 110

pad to the patch spaced from the means securing the patch to the garment, whereby relative movement between the pad and the garment may be permitted by stretching of a portion of the patch.

3. A garment having secured to its surface a patch of elastic stretchy material by stitching at the edge of said patch, and a pad of cushioning material attached to said patch, the means securing the pad to the patch lying wholly within and spaced from the stitching securing the patch to the garment.

4. A garment having a patch of elastic stretchy material attached by its edge to the surface of said garment, and a pad of cushioning material mounted on said patch, said pad being substantially similar in shape to said patch but smaller in area and centrally mounted on said patch with respect thereto to leave the margin of said patch free from said pad.

In witness whereof I have hereunto set my hand and seal this 18th day of March 1921.

DENNIS C. O'SHEA. [L. s.]
